(57) **CLAIM**

The ornamental design for a mosquito killing device, as shown and described.

DESCRIPTION

FIG. 1 is a front elevational view of a mosquito killing device embodying the design of the present invention.

FIG. 2 is a rear elevational view of the mosquito killing device shown in FIG. 1.

FIG. 3 is a left side elevational view of the mosquito killing device shown in the prior figures.

FIG. 4 is a right side elevational view of the mosquito killing device shown in the prior figures.

FIG. 5 is a plan view of the mosquito killing device shown in the prior figures; and,

FIG. 6 is a bottom view of the mosquito killing device shown in the prior figures.
